UNITED STATES PATENT OFFICE.

HUGH G. McGIRR, OF AUBURN, NEW YORK.

AXLE-BOX.

SPECIFICATION forming part of Letters Patent No. 272,293, dated February 13, 1883.

Application filed September 19, 1882. (No model.)

To all whom it may concern:

Be it known that I, HUGH G. McGIRR, of Auburn, county of Cayuga, State of New York, have invented new and useful Improvements 5 in Axle-Boxes, of which the following is a full and exact description, reference being had to the accompanying drawings, making part of this specification.

The object of this invention is to cause the 10 distribution of a lubricant over the wearing-surface of an axle during the revolution of the wheel; also, to provide means for taking up the shock incident to any sudden lateral movement of the wheel; also, to provide simple and 15 effective means for preventing the nut from turning upon and dropping off the axle while the wheel is in motion. These objects I attain by means of one or more tubular spirally-slotted metal bushings fitted within the box 20 of the wheel-hub and adapted to turn upon the axle, the spiral slot acting as a conveyer for carrying the lubricant over the wearing-surface of the axle while the wheel is in motion, and the bushing thus formed serving as 25 a spring bumper or cushion when the wheel is thrown to either side, so as to bring the end of the bushing against an abutment on the axle. The last object I attain by means of a 30 cap formed as herein described, and fitted both upon the nut and the axle.

In the drawings, Figure 1 represents a portion of an axle, partly in section, with my improvements applied. Fig. 2 is an end view of the cap detached. Fig. 3 is a section through 35 the hub-box, taken on the line $x-x$, Fig. 1. Fig. 4 represents one of the tubular spirally-slotted bushings.

Referring by letter to the drawings, A indicates the body of the axle, and A' one of its 40 arms. The box C of the wheel-hub has its inner end enlarged, so as to form a cap, C', which fits over one end of a collar, D, forged upon or cast and shrunk on the axle. The outer end of the box passes under an annular flange, 45 E, formed upon the inner side of a nut, E', that is fitted upon the screw-threaded end of the axle-arm. This arrangement, while admitting of the free rotation of the box around the axle-arm, effectually prevents the entrance 50 of dirt and sand between the arm and the box. Upon the axle-arm, between the nut and the collar, which is located at the junction of the

axle-arm and the body of the axle, I arrange a pair of tubular spirally-slotted steel bushings, F, which rotate with the box by which they are inclosed. In order to cause these two bushings to thus rotate with the box, I fix 55 within the middle of the latter a collar or ring, G, provided with notches g, and upon one end of each bushing I provide a lug, H, which is received in one of the notches in the ring. In 60 this way the bushings will be locked to the box, and hence will rotate simultaneously with the same. As the wheel, with its hub-box and these bushings, revolves, the lubricant 65 which has been supplied will be carried around the axle-arm and also distributed from end to end thereof by the walls of the spiral slots in the bushings. These spirally-slotted steel bushings also serve as elastic cushions for taking 70 up the shock incident to any lateral play of the wheel, and serve to prevent jarring and rattling. The inner end of the bushing which is next to the axle-body abuts against the collar between the body and the arm, while the 75 outer end of the remaining bushing abuts against the nut. To prevent the nut from turning and dropping off while the vehicle is in motion, I provide a cap, I, which is adapted to fit snugly upon the nut. This cap has an 80 oblong opening, i, in which the correspondingly-shaped outer end of the axle-arm is fitted. Hence while the axle prevents the rotation of the cap the latter will prevent the nut from 85 turning, since the inner side of the rim of the cap is made polygonal-shaped, so as to conform to the shape of the nut. To hold this cap upon the nut and the axle-arm, a set-screw, K, is fitted in a screw-threaded socket, L, in the end 90 of the axle-arm and the screw tightened up against the cap.

Having thus described my invention, what I claim is—

1. A removable tubular spirally-slotted metal bushing, fitted within the box of the wheel-hub, and adapted to fit and turn upon the 95 axle-arm, substantially as described.

2. The combination, with the box of a wheel-hub, of the two spirally-slotted tubular metal bushings fitted within the box, and connected 100 at their meeting ends with a collar which is rigid with the box, substantially as described.

3. The combination, with the box of a wheel-hub, having one end fitted over a collar on the

axle and its remaining end fitted within an annular flange of a nut which is secured upon the end of the axle, of the tubular spirally-slotted metal bushings loosely fitted upon the 5 axle-arm and connected with the box, the outer ends of the two bushings being respectively opposed to the said nut and collar, substantially as described.

4. The ring or collar formed in or with the 10 box, and having lugs or notches for preventing the bushing from turning therein, substantially as described.

5. The combination, with the nut fitted upon the end of the axle-arm, of the cap fitted 15 upon the nut and adapted to embrace the squared-sides thereof, and having an elongated opening in which the end of the axle is received, said cap being secured to the axle-arm by a set-screw, substantially as described.

20 6. The axle provided with the screw-thread-

ed end and the flanged nut E E', in combination with cap I, provided with the oblong slot *i*, which is adapted to fit over the shouldered end of the axle and embrace the sides of the nut, substantially as and for the purpose described.

7. The axle provided with the external and internal screw-threaded end, the flanged nut E E', cap I, provided with the oblong slot *i*, adapted to fit over the shouldered end of the 30 axle, and also to embrace the sides of the nut, in combination with the set-screw K, all arranged and operating substantially as described.

In testimony whereof I have hereunto set my 35 hand.

HUGH G. McGIRR.
